AUGUSTA.

UNITED STATES PATENT OFFICE

2,143,012

COMBINED PEN AND PENCIL HOLDER

Joseph C. Kanipe, Washington, D. C.

Application August 5, 1937, Serial No. 157,605

2 Claims. (Cl. 24—11)

My invention relates to new and novel improvements in a combined pen and pencil holder and point protector.

One of the principal objects of my invention is to provide a pen and pencil holder for reliably holding pens or pencils, equipped with means for protecting the points thereof.

Another object of my invention is to provide a device of the above described character equipped with means whereby pencils or pens of various lengths are reliably secured in the holder and the points protected.

A further object of my invention is to provide a device of the above described character equipped with means for retaining lengths of lead accidentally dislodged from mechanical pencils or the like in order that the same may be reinserted in said pencil for use.

Other objects and advantages will be apparent from the following description, appended claims and annexed drawing.

Referring to the drawing wherein like reference characters designate like parts throughout the several views:

Fig. 1 is a front elevation of my invention.

Fig. 2 is a sectional view taken on the line 2—2 of Fig. 1.

Fig. 3 is a detail vertical sectional view on an enlarged scale.

Fig. 4 is a rear elevation of the sleeve and finger.

Fig. 5 is a side elevation of the sleeve and finger.

Fig. 6 is a sectional view on the line 6—6 of Fig. 3.

Fig. 7 is a front elevation of the clamp for securing the holder to a garment.

Fig. 8 is a cross sectional view illustrating a modified form of barrel and sleeve.

In practicing my invention, in the preferred form illustrated in Figures 1 to 7 inclusive of the drawing, I employ a barrel 10 having a closed end 11 and an opened end 12 flared as at 13. The flared portion coacts with a pencil 14 to guide the same when it is being inserted within the barrel

10. The upper end of the barrel, adjacent the flared portion 13, is provided with a clamp fastener 15 for securing the barrel to a garment and is preferably constructed of a piece of flat metal 16, bent to form upper and lower jaws which will allow the garment to be slipped between them. For holding the jaws in place and operating them, there is provided a second U-shaped piece of metal 17 enclosing the jaws and provided with a lever 18. These jaws are preferably provided with

teeth 19 for more securely holding the material inserted between them.

The barrel, intermediate of the ends, is formed with a plurality of elongated slots 20 for receiving an offset end 21 of a pencil or pen positioning means 22.

The means 22 comprises a sleeve 23 mounted on the barrel 10 and formed with an elongated resilient finger 24 terminating in the offset end 21.

The upper end of the barrel adjacent the flared portion is formed with an aperture 25 for receiving an offset rounded end 26 of a leaf spring 27, said leaf spring being secured to the barrel by means of rivets 28 or the like at the opposite end.

The offset section 21 of the finger 22 inclines inwardly and downwardly towards the barrel, the lower end being bent upon itself to form a locking means, the upper end being rounded at the jointure with the finger proper.

In use, the sleeve is slid upwardly or downwardly as the case may be to permit the offset end 21 to move into one of the desired slots 20 and move downwardly a sufficient distance to permit the lower bent end of the offset section to engage the inner periphery of the barrel adjacent the lower face of the slot, as clearly illustrated in Fig. 3 of the drawing. A pencil or pen is then inserted, the lower tapered end engaging the lower end of the offset section 21 as illustrated in Fig. 2 of the drawing. When the lower end of the offset section engages the tapered side of the pencil, the offset section is prevented from moving outwardly due to the lower end of the section engaging the inner peripheral wall of the barrel adjacent the lower face of the slot 20. Due to the resiliency of the lower offset section, the tapered end of the pencil or pen effects a clamping or locking of the offset end in relation to the barrel to prevent lateral movement of said end. When a pen or pencil is inserted in the barrel, the rounded end 26 of the spring 27 will effect a clamping of the pencil or pen within the barrel and prevent accidental dislodgement therefrom, as clearly illustrated in Fig. 2 of the drawing.

When it is desired to secure a pencil or pen of relative short length within the holder, the sleeve is gripped by the fingers and an upward sliding movement applied thereto. This movement effects a camming action between the upper face of the slot 20 and upper inclined face of the offset section 21. Continued upward movement of the sleeve causes the upper inclined face of the offset section to engage the upper face of the slot 20 with the resultant engagement of the lower end of

the offset section with the outer peripheral face of the barrel above the upper face of the slot 28. Obviously, continued upward movement of the sleeve permits of the offset section 21 moving into the adjacent slot formed thereabove. When a pencil or pen of relatively longer length is to be held within the barrel, the sleeve is moved upwardly to effect a disengagement of the offset section from within the slot 28 in the same manner as heretofore described.

In order to move the offset portion downwardly for engagement within a subjacent slot, the sleeve is rotated on the barrel a sufficient distance to permit the offset section to move downwardly without snapping into the slot it has been priorly disengaged from. In this position the offset portion is moved downwardly, through the medium of the sleeve, to a position laterally of a slot it is desired to position the offset section in. A slight rotation of the sleeve will permit the offset section to register with the slot and snap therein.

From the foregoing, it will be apparent that pencils or pens of various lengths are reliably secured within the holder a sufficient distance to prevent the points of pencils from engaging the closed bottom of the barrel and being broken. In the instances of mechanical pencils, should the points be accidentally dislodged therefrom, the same will be retained within the lower part of the barrel and may be extracted therefrom for further use.

As illustrated in Fig. 8 of the drawing, the barrel may be formed with an offset longitudinally extending rib 30 operable within an offset section 31 of the sleeve 23. This construction prevents rotation of the sleeve relative to the barrel. To effect sliding action of the offset section 21 downwardly and prevent the same from moving into undesired slots during the course of its travel downwardly, the pencil 14 is inserted within the

barrel in a manner that the vertical sides will prevent the lower ends of the offset section from moving into the barrel. The metal of the barrel being relatively thin, the lower rounded end of the offset section will be cammed outwardly as the same moves downwardly, thus eliminating the necessity of rotating the sleeve relative to the barrel to position the offset section in a subjacent slot.

It is to be distinctly understood that while I have illustrated and described my invention in connection with securing pencils or pens in a manner to protect the points thereof and which is adapted to be reliably secured to a garment or the like, the same may be utilized for other articles such as tools and the like without departing from the spirit of the invention or scope of the appended claims.

Having described my invention, what I claim is:

1. A device of the character described comprising a barrel formed with a plurality of longitudinally arranged slots, and an adjusting means slidably mounted on said barrel and fashioned with a section extending through one of said slots for engagement with a pencil within said barrel in a manner to engage the tapered end of the pencil to form a stop therefor.

2. A device of the character described comprising a barrel formed with a plurality of longitudinally arranged slots, an adjusting means slidably mounted on said barrel and fashioned with a section extending through one of said slots for engagement with a pencil within said barrel in a manner to engage the tapered end of the pencil to form a stop therefor; said section bent upon itself to form a hook engaging the inner periphery of the barrel to prevent displacement of said section by the pencil.

JOSEPH C. KANIPE. 40
